UNITED STATES PATENT OFFICE

JOHAN VIKTOR BLOMQVIST, OF STOCKHOLM, SWEDEN, ASSIGNOR TO AKTIEBOLAGET ATMOS, OF STOCKHOLM, SWEDEN, A CORPORATION OF SWEDEN

ROTATING BOILER

Application filed February 6, 1928, Serial No. 252,332, and in Sweden February 16, 1927.

Rotating steam generators consisting of one or more rotary receptacles partly filled with water have already been proposed, such boilers being built into the furnace and adapted to be used for very high steam pressures, for instance about 100 atmospheres. In this construction it is of course important that these receptacles are given as large a diameter as possible, but in proportion as the diameter is increased the thickness of shell must be heavier and thus the heat tension in the material will be increased. This is the reason why the outside diameter cannot be larger than 12 inches to 14 inches at a steam pressure of 100 atmospheres, and thus it will be necessary to provide a relatively large number of receptacles in the furnace if great quantities of steam are to be produced in a unit.

According to the invention this inconvenience is eliminated by the boiler construction, referred to in the following description, which consists of a number of tubes arranged in the furnace around a common axis. These tubes are fastened at their ends into end sections having the shape of annular receptacles, into which the fed water is introduced in order to be carried therefrom into the steam generating tubes, as the latter during the rotation of the steam generator are moved downwards below a predetermined water level in the end sections. The steam generated in the tubes passes from their ends into the annular end sections from which it is carried to the place of consumption after having passed through a superheater, if so desired. As soon as the tubes pass below the predetermined water level the steam leaving them must overcome the resistance of the water columns in the annular end sections, and thus it is evident that also the flow of the water into the pipes will be impeded by the steam flowing out in such a way that the resulting water level in the annular end sections in reality will not represent the effective pressure head. By further developments of the present invention this disadvantage will also be removed by conducting the steam from the boiler tubes through smaller tubes asso-

ciated with the larger ones in such a way that the water may flow freely into the boiler tubes around these smaller tubes and simultaneously the steam pass freely from the boiler tubes, with the result that the whole water heads in the end sections will form effective pressure heads for introducing the feed water into the boiler tubes. 55

Other objects of the invention will be clearly understood from the following detailed description of the same. 60

The invention is clearly illustrated in the accompanying drawings, in which

Figure 1 is a longitudinal section through a steam generator according to the invention, 65

Figure 2 is a cross section through the same,

Figure 3 is a longitudinal section through one of the end sections in a further development of the steam generator shown in Figure 1, 70

Figure 4 is a longitudinal section through another embodiment of the invention,

Figure 5 is a cross section through a modified form of the construction shown in Figure 4, 75

Figure 6 is a partial longitudinal section through a modified form of the embodiment shown in Figure 4,

Figure 7 shows a partial view in cross section and elevation of another method of feeding the water, 80

Figure 8 shows another modification in cross section of the device shown in Figure 1,

Figure 9 is a modification shown in cross section of the stuffing box disclosed in Figure 4, 85

Figure 10 is a longitudinal section of a boiler according to the apparatus shown in Figure 4 and showing the general arrangement of a preheater, revolving steam generator and superheater, 90

Figure 11 is a cross section of the arrangement shown in Figure 10, and

Figure 12 is still another modification of the device shown in cross section.

Referring to the drawings in which similar reference characters indicate like parts in the various views, the steam generator as shown particularly in Figures 1 and 2 consists of 100

a number of boiler tubes 1 of relatively small diameter arranged around one common axis. One concentric group of tubes is shown in the drawings but of course the boiler may 5 also consist of two or more groups of tubes arranged concentrically in relation to each other. The set of tubes or the rotor is placed in the furnace and a superheater as well as a preheater may be arranged above the boiler proper. The feed water is preferably pre- 10 heated in the feed water heater by means of the fuel gases flowing from the rotor at a temperature corresponding to the boiling point at the steam pressure existing in the boiler, and in such condition the water flows through the pipe 2, a hollow journal 3 and the distributing pipes 4 to the receptacle 5 from which the water during the rotation of the boiler is gradually distributed into 15 the tubes 1 in which the generation of the steam and, as the case may be, the preheating of the feed water takes place. The steam generated in the tubes 1 passes into the annular receiving chamber 6 and from said 20 chamber through some of the rotor tubes 1 and pipes 4 to the journal 3 from which it is carried to the place of consumption through the pipe 7. The rotor tubes 1 have a smaller diameter at their ends than throughout their 25 length. In this way pockets are formed in the tubes 1 in which a certain quantity of water is always confined. During each revolution of the rotor the body of water therein will be correspondingly displaced in the 30 tubes in such a way that the tubes are always cooled effectively. The rotor is driven in any known way as for instance by means of a 35 pulley 8 and a belt.

The embodiments of the invention shown in 40 Figures 3 to 9 inclusive are best explained by referring to their mode of operation, especially as the details may vary in different ways within the limits of the invention.

According to Figure 3 the feed water, pre- 45 heated or not, flows through a central, preferably stationary pipe 2' and further through the radially arranged pipes 9 into the end section 10 forming an annular receiving chamber and from this chamber it passes 50 successively to the different rotor tubes 6' as these, during the rotation of the steam generating rotor, are travelling below the water level as for example in the instance of the lower tube 6'. The steam generated in 55 the rotor tubes 6' passes out through the smaller tubes 11 which are centrally arranged in the rotor tubes and project into the latter a suitable distance. These tubes 11 extend through the annular end receptacle 10 and discharge into the hollow journal 14 surrounding the feed water pipe 2'.

In the embodiment of the invention shown 60 in Figures 4 and 5 the feed water is carried through the conduits 1^a and the central pipe 2'' into the chamber 3' from where it flows

through the pipe 4' into a receiving chamber 5' which is journalled, together with the set of pipes 6'' in bearings 7' and rotated for instance by means of the belt pulley 8. The receptacle 5' is partially filled with the feed 70 water and delivers such water through the radially arranged pipes 9' to the annular end receptacle 10' from which it is distributed to the steam generating tubes 6'' during the rotation of the steam generator in the manner mentioned above. If the number of pipes 9' corresponds to the number of tubes 6'' the end section 10' may also be carried out without any annular receiving chamber and only consist of a solid ring provided with cavities 75 opposite the ends of the tubes 6'' (see Figure 5). The pipes 9' are then fitted into these cavities. As shown in Figure 4, the pipes 9' open into the end section 10' or the cavities shown in Figure 5 in such a way that the tubes 80 6'' during the rotation of the steam generator will never be entirely emptied, so that the same result is secured as by the above mentioned restrictions placed at the ends of the tubes 1. If, during a revolution, more water 85 is fed into the tubes 6'' than the quantity that can be evaporated during the cycle of revolution, the surplus is carried back through the pipes 9' to the central receptacle 5' as soon 90 as the orifices of the latter pipes arrive above the water level in the receptacle 5'. The pipes 9' open into the receptacle 5' at a suitable 95 distance from the inner distance of the shoulder of the latter, that is, they extend radially 100 a certain distance into the receptacle.

The steam generator with the receptacle 5' and the set of tubes 6'' is journalled in a collar thrust bearing 20 at one end in such a way that it can not slide axially at this place while the opposite end of the generator is allowed to slide axially. The bearing 20 may of course be substituted by a ball thrust bearing. A set of arms or spokes 21 is fastened to the journal 23 of the receptacle 5' and at the circumference provided with heads 22 carrying the tubes 6'' in such a way that the latter are allowed to slide longitudinally. In this way the tubes 6'' are able to expand freely when heated independently of the expansion of the receptacle 5'. 110

The steam generated in the tubes 6'' flows 115 through the pipes 11' to a chamber 12 and from said chamber through the openings 13 into a pipe 14' and through the conduit 15 to the place of consumption. A pipe 14' does not rotate but rests at one end in the wall of the chamber 12. At its opposite end the pipe 14' communicates with the conduit 15, the pipe resting in a stuffing box 16, which prevents the water from the conduit 1^a passing 120 onto the conduit 15 and there mixing with the steam. The packing material in the stuffing box 16 is kept in its place by means of an apertured bushing 19 and a cover 18 which also compresses the packing 17 thus prevent- 125

ing the steam in the conduit 15 from escaping to the atmosphere. The opposite end of the pipe 14' opens into the receptacle 5' in order to carry off also the steam generated therein.

5 Also in this embodiment of the invention steam may be drawn off from the tubes 6'' at the opposite side by means of pipes corresponding to the pipes 11'. Also in this case the steam is carried through a hollow journal, but of course an extra stuffing box must be used which is avoided by the arrangement shown in the drawings.

Figure 6 shows an embodiment of the pipe arrangement for the water inlet and the steam outlet to and from the tubes 6''. Here the tube 24 is placed inside of the tube 25. As these tubes rotate below the water level the water will first flow through the smaller tubes 26 into the tubes 24 and then to the tubes 6''. The steam from the latter will then pass into the annular space between the tubes 24 and 25 where it need only overcome the resistance of the water column standing above the tube 25. By this arrangement the steam will have 25 a free outlet for all practical purposes to the steam space in the receptacle 5'. When the tubes 6'', during the rotation of the steam generator, arrive above the water level in the receptacle 5', the excess water will flow back 30 through the annular space between the tubes 24 and 25 into the receptacle 5' and the steam escapes through the tube 24. The tubes may of course also be arranged in a different way, the essential feature of the construction being 35 that the water is allowed to flow freely into the tubes 6'' and the steam to escape freely from the same.

Instead of feeding the water into the receptacle 5', it may be fed in through the hollow journal 2'' to the chamber 12 and from there through the pipes 11' directly into the tubes 6'', as shown in Figure 7. The steam passes from the tube 6'' through the pipes 9' to the receptacle 5' from where it escapes 40 through the pipes 14' to the superheater (see Figures 10 and 11).

The main object of the receptacle 5' is to form a water reservoir for controlling the quantity of water introduced into the steam generator according to the position of the water level in the same.

Figure 8 shows a modification of the boiler shown in Figures 1 and 2. According to this modification the water enters through the pipes 1^b and 2^b into the chamber 3^b. From said chamber the water is distributed through the tubes 11^b into the steam generating tubes 6^b. The steam escapes from these tubes to the pipes 9^b to the chamber 4^b from which it is carried through the pipes 14^b and 15^b to the superheater.

Another modification is shown in Figure 12. According to this an annular chamber 10^c is placed at each end of the assemblage of tubes 6^c and connecting their restricted ends.

The receptacles 10^c are connected with the chambers 3^c and 4^c by the tubes 11^c and 9^c. The water is carried through the tubes 11^c by means of one of the receptacles and the steam escapes from the tubes 6^c by means of the other receptacle through the pipes 9^c and the pipe 14^c connected to the superheater.

In the modification shown in Figure 3 instead of feeding the water through the pipe 2' it may be fed in through the hollow journal 14 and the pipes 11 into the steam generating tubes 6'. In this case the steam from the tubes 6' passes through the pipes 9 and the central tube 2' into a superheater.

The steam generator may have its axis of rotation either horizontally disposed or slightly inclined.

In the rotating steam generators hitherto known the stuffing boxes used between the rotating and the non-rotating parts must be lubricated by means of oil in order to keep the packing material as soft as possible, as this material which is soaked with lubricant from the beginning will be damaged very soon at the temperatures in question so that the joint soon will be useless, if it is not lubricated. Figure 4 shows a device in which the packing instead of being lubricated by oil, is cooled by water. The water is preferably taken from the pressure pipe of the feed water pump before getting into the pre-heater and carried to a chamber provided around the packing through the pipe 48. From here it passes through the lantern 49 in the direction of the arrow along the packing and through the openings 50 in the annular chamber between the pipes 2'' and 14' and together with the feed water through the chamber 3' into the steam generator.

The cooling of the stuffing box may also be effected by cold water of a lower pressure than the boiler pressure, for instance at atmospheric pressure. Figure 9 shows such a modification of the stuffing box disclosed in Figure 4. The cooling water enters 105 through the pipe 48 and passes around the stuffing box through the apertured bushing 49 to the inner annular chamber 51 between the inner circumference of the stuffing box and the pipe 2''. From said annular chamber 110 water is carried into the open air through the opening 50.

Figures 10 and 11 show the general arrangement of a boiler plant according to the invention with preheater, revolving steam generator and superheater. The water is fed in by a feed pump through the pipes 30 into the preheater 31 consisting of straight, preferably gilled tubes connected in series. From the top of the preheater the heated water enters the pipe 1^a and is introduced into the steam generating tubes 6''. The steam leaves the revolving steam generator through the pipes 15 and is thereby conducted to the superheater 32 from where it passes to the 130

place of consumption by means of the pipe 33. The fuel gases pass through the spaces between the fuel generating tubes 6" circum-flowing the superheater tubes 32 and over the preheater 31 in countercurrent to the water within the latter approaching the exit channel 34 and escaping through a smoke stack, not shown.

10 The above modifications are merely illustrative and it is understood that any modifications as come within the spirit of the following claims are included in the invention.

I claim:—

15 1. A slowly rotating rotary steam generator comprising a feed water chamber, a steam extracting chamber, a plurality of steam generating tubes positioned in substantially equally distant spaced relation around a common axis of rotation, means for imparting 20 external heat to said tubes, pipes for introducing feed water from said feed water chamber into said tubes and another series of pipes connected with said tubes for withdrawing the generated steam therefrom and 25 leading it to the steam extracting chamber.

2. A slowly rotating rotary steam generator comprising a journalled hollow rotor structure having a substantially horizontal axis of rotation and having feed water and steam receiving spaces, a plurality of substantially straight steam generating tubes mounted on the said rotor structure in substantially equally distant spaced relation around the axis of rotation substantially parallel to said 30 axis, means for imparting external heat to said steam generating tubes, means for introducing feed water into and withdrawing steam from the said feed water and steam receiving spaces of the said hollow rotor structure during the rotation of the generator, and separate connections between each of the 35 said steam generating tubes and the said feed water and steam receiving spaces of the hollow rotor structure for allowing separate entrance of feed water into and escape of generated steam from each of the said steam generating tubes when moving below a substantially horizontal level of the feed water in the hollow rotor structure at the rotation of the 40 generator, each of the said separate connections between each of the said steam generating tubes and the said feed water and steam receiving spaces of the rotor structure being constructed and arranged to prevent the feed 45 water in the said steam generating tube from flowing entirely out of the said tube through said connection when moving above the feed water level in the hollow rotor structure at the rotation of the generator.

50 60 65 3. A slowly rotating rotary steam generator according to claim 2 in which the hollow rotor structure comprises a feed water and a steam receiving chamber extending around the axis of rotation of the generator at opposite ends thereof and interconnected by

means of the steam generating tubes, each of the said steam generating tubes having portions of reduced inner diameter at both ends communicating with the said chamber.

4. A slowly rotating rotary steam generator according to claim 2 in which the hollow rotor structure comprises a feed water and a steam receiving chamber extending around the axis of rotation of the generator at opposite ends thereof, each of the said steam generating tubes having portions of reduced inner diameter at both ends connected by means of pipes to the said feed water and steam receiving chambers.

5. A slowly rotating rotary steam generator according to claim 2 in which the hollow rotor structure comprises a central receptacle for receiving feed water and steam and the steam generating tubes are mounted around the said receptacle in radially spaced relation thereto and each are connected to the steam and water spaces of the said receptacle by means of radially extending separate pipes.

In testimony whereof I have signed my name to this specification.

JOHAN VIKTOR BLOMQUIST.
